UNITED STATES PATENT OFFICE.

PAUL CHARLES BUTTE AND CHARLES FELIX BUTTE, OF SAN FRANCISCO, CALIFORNIA.

DESIGN FOR AN ARCH.

46,798.

Specification for Design.

Patented Dec. 29, 1914.

Application filed January 26, 1914. Serial No. 814,596. Term of patent 7 years.

To all whom it may concern:

Be it known that we, PAUL CHARLES BUTTE and CHARLES FELIX BUTTE, residing at 683 Howard street, San Francisco, in the county of San Francisco and State of California, have invented a new, original, and ornamental Design for Arches, of which the following is a specification, reference being had to the accompanying drawing, forming part thereof.

Figure 1, is a side view of an arch showing our new design. Fig. 2, is a detail showing the manner of supporting said arch. Fig. 3, is a detail showing alternate drop-light design.

In the illumination of city streets and especially in thickly populated districts, it is desirable at the crossing of streets that night illumination be arranged so that no light supporting posts shall obstruct the traffic of the streets, but that lights be provided to satisfactorily illuminate such crossings at all times. Such illumination is found to be best accomplished by lights suspended over said streets or crossing. The weight of suitable lamps or lights is considerable and the

effect of storms must be provided against by the use of a supporting structure of considerable strength. For accomplishing this most effectively, and ornamentally, we provide a structural metal arch spanning the street or crossing having its base supports upon the sidewalk or corners, and provided with lamps or globes suspended therefrom. By this means, all shadows are avoided, and a proper distribution and division of light is obtained even between the vehicles and cars. Heretofore, shadows falling from passing vehicles caused by lights located on one side have been the source of danger, that by the use of our arch is avoided. At the same time, the appearance of our arch is such as to add to the beauty and effectiveness of the illumination.

We claim:—

The ornamental design for an arch as shown and described.

PAUL CHARLES BUTTE.
CHARLES FELIX BUTTE.
